UNITED STATES PATENT OFFICE.

EUGENE PHELPS, OF PITCHFORK, WYOMING.

CHAIN WRENCH.

1,196,479.

Specification of Letters Patent. Patented Aug. 29, 1916.

Application filed April 16, 1915. Serial No. 21,786.

To all whom it may concern:

Be it known that I, EUGENE PHELPS, a citizen of the United States, and a resident of Pitchfork, in the county of Park and

5 State of Wyoming, have invented a new and Improved Chain Wrench, of which the following is a full, clear, and exact description.

This invention relates to wrenches and has 10 to deal particularly with the type known as "chain" wrenches.

The general objects of the present invention are to improve and simplify the construction and operation of wrenches of the 15 character referred to so as to be reliable and efficient in use, comparatively simple and inexpensive to manufacture, and so designed as to be easily and quickly applied to an object to be turned, and to grip such object 20 with great power.

A more specific object of the invention is the provision of a wrench having a single jaw and with which coöperates a chain linked at one end to the jaw, and any link 25 of the chain is adapted to be engaged with a tooth carried by the jaw at a point spaced from the link that unites the chain with the jaw, whereby the said jaw and chain can grip an object to be turned, and further- 30 more, the wrench may have a hollow handle into which the free end of the chain extends so as to be out of the way and not interfere with the proper gripping or operation of the wrench.

35 Still another object of the invention is the provision of a wrench which is extremely narrow so that it can be used in places where wrenches of the present type, due to their bulkiness, cannot be used.

40 With such objects in view, and others which will appear as the description proceeds, the invention comprises various novel features of construction and arrangement of parts which will be set forth with particu- 45 larity in the following description and claims appended hereto.

In the accompanying drawing, which 50 illustrates one embodiment of the invention, and wherein similar characters of reference indicate corresponding parts in all the views, Figure 1 is a side view of the wrench; Fig. 55 2 is an edge view thereof; Fig. 3 is a perspective view of the jaw portion of the wrench; Fig. 4 is a perspective view of the toothed jaw detached; Fig. 5 is a sectional view on the line 5—5, Fig. 1; Fig. 6 is a

sectional view on the line 6—6, Fig. 1; Fig. 7 is a side view of a modified form of the invention; and Fig. 8 is a sectional view on the line 8—8, Fig. 7.

60

Referring to the drawing, A designates the handle of the wrench, which is formed with an enlarged jaw portion 1 which is integral with the handle. The handle may be made of sheet metal shaped into the desired form, but it is to be understood that the handle may be made solid, such as by casting or drop forging, as shown in Fig. 7. The jaw 1 has its operative portion disposed at a slight angle to the axis of the handle, 70 and carries a serrated hard steel jaw element 2. This jaw element is a piece of hard steel in bar form and formed with serrations 3. On opposite sides of the jaw element are dovetails 4 which fit in dovetail 75 recesses 5 in the jaw portion of the handle. The jaw piece 2 has one end formed into a hook 6 that projects from the jaw portion 1 of the handle and is approximately parallel with the length of the handle.

80

Coöperating with the jaw element 2 is a chain 7 for gripping an object to be turned. This chain is connected by link members 8 with the head or enlarged end of the handle, such link members being pivoted to swing 85 on the pivot rivet 9. By linking the chain to the handle in this manner the chain is more readily adaptable to grip objects of different diameters. The hook 6 serves to fasten the free portion of the chain to the 90 handle by a link of the chain being engaged with the hook, whereby the chain can be fastened in loop formation about an object and hold the latter against the serrations of the jaw element, as shown in Fig. 1. The 95 free end of the chain may be inserted through an opening 10 into the hollow of the handle A so as to be out of the way. The serrations 3 are pitched away from the hook 6 so that they will bite into an object 100 when the handle is turned in one direction or anti-clockwise in Fig. 1 and slip around on the object when the handle is turned clockwise, whereby the tool can be operated by a sort of ratchet action.

105

In the modification shown in Figs. 7 and 8 the jaw element 2' is a stamp of U-shaped cross-section which has its hollow side fitted to the tongue 11 on the handle A', and the jaw element 2' is secured in place in any 110 suitable manner, as by a rivet 12. Hook 13 with which the chain 7' is adapted to en-

gage is formed integral with the handle, which latter is a casting or forging.

The hook 6 or 13 may be used as a bottle cap remover, such use being indicated by the dotted lines in Fig. 7.

From the foregoing description, taken in connection with the accompanying drawing, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made when desired as fall within the scope of the appended claims.

Having thus described my invention, I claim as new and desire to secure by Letters Patent:

1. A chain wrench comprising a handle having at one end an enlargement provided with an arcuate face, the chord of which is disposed at an acute angle to the length of the handle, and said face being provided with serrations and having a continuation forming a hook making with the handle a

recess, a link pivotally connected with the handle at the side thereof opposite from the hook, and a chain having one end connected with the free end of the link and the other end of the chain free, the links of the chain being engageable with the hook. 30

2. A chain wrench comprising a handle having a jaw portion at one end, a jaw piece formed with an arcuate face, the chord of which forms an oblique angle to the length of the handle, and said jaw piece having serrations in its arcuate face, means for fastening the jaw piece rigidly to the handle, there being a hook-forming extension at one end of the jaw piece and co-operating with the adjacent portion of the handle to form a recess, and a chain fastened to the handle and having its links engageable with the hook, whereby the chain cooperates with the jaw piece to grip an object. 35 40 45

In testimony whereof I have signed my name to this specification in the presence of two subscribing witnesses.

EUGENE PHELPS.
